UNITED STATES PATENT OFFICE.

ANNING S. PRALL, OF PORT RICHMOND, NEW YORK.

PROTRACTING DEVICE.

SPECIFICATION forming part of Letters Patent No. 717,920, dated January 6, 1903.

Application filed February 13, 1902. Serial No. 93,975. (No model.)

To all whom it may concern:

Be it known that I, ANNIN S. PRALL, a citizen of the United States, and a resident of Port Richmond, in the county of Richmond 5 and State of New York, have invented certain new and useful Improvements in Protracting Devices, of which the following is a specification.

My invention, while relating to protracting devices generally, is designed more especially for use in plotting tracts and lots of land in books or on sheets of paper or other appropriate materials, its object being to provide a device of this character which, in 15 addition to being simple and cheap in construction, shall at the same time permit of the plotting of lots or tracts of lands or other forms upon materials that are more or less opaque and that, too, without the aid of 20 paper or other material that is of a transparent character.

To this end the invention consists of a suitable table and a graduated protractor, with an appropriate indicator and scale, all 25 as will be hereinafter more fully set forth.

Referring to the accompanying drawings, which form a part of this specification, Figure 1 is a plan view of a protracting device constructed in accordance with my 30 invention and showing by full and dotted lines the manner of using the same; Figs. 2 and 3, similar views of the device, showing also by full and dotted lines the manner of using the same, with portions of the 35 table and the protractor of each broken away for convenience of illustration; Fig. 4, a vertical section of a portion of the device, taken in the plane x x in Fig. 1; Fig. 5, a similar vertical section of a portion of the same, 40 taken in the plane y y in Fig. 1; and Fig. 6, a face view of the scale detached.

In all the figures like letters of reference are employed to designate corresponding parts.

A indicates a table upon which the plotting is effected, the same being constructed 45 of wood or other appropriate material in plate form and of the required thickness to suit it to the uses for which it is intended. I prefer, however, to construct it of wood 50 and in approximately rectangular contour, with its several angles or corners rounded off, and to strengthen the same and prevent it from splitting or warping by a strip or strips a of appropriate material that is or are se-

cured to its edges and project above and below its upper and under surfaces, as shown. As thus constructed the table A, which is provided with a protractor B, that is or may be divided into degrees and minutes, and, when made as a complete circle, is preferably, 55 though not necessarily, divided into quadrants, which are separated from one another by the respective letters "N" "E" "W" "S" and the numbering of the degrees of each quadrant commenced with a new series of figures. 60

Coöperating with the protractor B is an indicator C, by means of which the center of the protractor may be indicated when the same is covered by the paper or other article 70 on or in which the protraction is to be made. This indicator is preferably pivoted to the table A outside of the periphery of the protractor in a stand D, which is secured to the upper surface of the former by screws c. As 75 thus arranged the indicator may be swung upward into a vertical position, as shown by dotted lines in Fig. 4, when it is desired to superpose a sheet of paper or other article upon the protractor or otherwise or downward into an approximately horizontal position, with its point resting upon the sheet or other article directly over the center of the protractor, as shown by full lines in that figure. With the protractor and indicator thus 80 described is employed a ruler or scale E, which may be graduated with any appropriate units of measure or otherwise, as may be desired. In the form shown in the drawings, however, which is the one I prefer in practice, the scale is divided into chains and feet units, which are or may be appropriately numbered along the scale, as is common to scales and rules ordinarily in use, and forms no part of my present invention. 85

The various parts being constructed as above described and a sheet of paper or other article F resting upon the protractor, with the indicator turned downward and its point resting thereon directly over the center of the latter, the protraction of any plot or figure upon such sheet or article will be effected as follows: Assuming that the figure to be plotted is approximately rectangular in form and that the first line is to be drawn to represent 100 a length of three hundred feet running north by sixty degrees east, the second two hundred feet running south by thirty degrees 105

east, the third three hundred feet running south by sixty degrees west, and the fourth two hundred feet running north by thirty degrees west, the scale E will be placed upon 5 the paper or other article F on or in which the figure is to be plotted, with its edge against the downturned end of the indicator C opposite the zero-mark upon itself and in line with the sixtieth degree of the quadrant between 10 the letters "N" and "E," and the first line will be drawn with a pencil or other marker along the edge of the scale from the point e to the point f or from the zero-line to the line marked "300" thereon. With the scale 15 still held in this position against the indicator and in line with the sixtieth degree of such quadrant the paper or other article will be moved from the position shown by full lines in Fig. 1 into the position shown by dotted lines in that figure, by which the end f of the line thus drawn will be brought beneath the downturned end of the indicator, and the line itself will extend on the opposite side of that point along the edge of the scale, 20 as shown by dotted lines in that figure. With the paper moved into this position the scale will be turned around the point of the indicator, while its edge is held in contact therewith opposite its zero-mark until this edge is 25 brought into line with the thirtieth degree of the quadrant between "E" and "S," when the second line will be drawn along the edge of the scale from the point f to the point g or from the zero-mark to the mark indicated 30 by "200" upon the same. In this position the scale will be held and the paper or other article in or on which the protraction is being made moved under the same from the position shown in full lines in Fig. 2 to that 35 shown by dotted lines in that figure, when the termination g of the line last drawn will be brought opposite the zero-mark on the scale and beneath the indicator, and the line itself will extend on the opposite side of that point 40 along the edge of the scale, as shown by dotted lines in that figure. The scale will then be turned around the indicator-point, while its edge opposite the zero-mark is held against the same, until its edge comes opposite 45 the sixtieth graduation of the quadrant "S" and "W," when the third line will be drawn from the point g to the point h, or from the zero-mark on the scale to that indicated by "300" thereon. Upon the completion of 50 this line the sheet or other article will be moved along under the scale and indicator-point from the position shown by full lines in Fig. 3 to the position shown by dotted lines in that figure, when the termination h of this 55 line will be brought beneath the indicator-point and the line itself carried on the opposite side of the same, as shown by dotted lines in the last-mentioned figure. The movement of the paper or other article being thus 60 completed, a further rotation of the scale about the indicator, with its edge opposite the zero-mark in contact therewith, will be made 65

until its edge is brought into line with the thirtieth graduation of the quadrant between "N" and "W," when the fourth line of the figure will be drawn along its edge from the point h to the point e, or from the zero-mark to the two-hundredth mark and the figure completed, and so on, the scale serving to indicate the lengths of the several lines and the protractor to measure their angular relationships. 70

From the foregoing, therefore, it will be seen that I provide a protracting device which is not only simple and cheap in construction, 80 but admirably suited to the plotting of lots or tracts of land on sheets of paper or other material and in books, as well as to the drafting and drawing of other figures where the length of the sides and their angular relationships are to be indicated. 85

While in the foregoing I have described the form of apparatus which I prefer to employ in practice, I wish it distinctly understood that I do not limit myself strictly thereto, as 90 it is obvious that it may be modified in various ways and still be within the scope of the invention.

Having now described my invention and specified the best means contemplated by me 95 for carrying it into practice, I claim and desire to secure by Letters Patent of the United States—

1. The combination, with a table upon which the plotting may be effected provided 100 with a protractor, of an indicator provided with a downwardly-extending point for indicating the center of the protractor, and means for supporting the said indicator and permitting of it being moved toward and away from 105 the protractor, the supporting means being located at a fixed point with respect to the center of the protractor, substantially as described.

2. The combination with a table upon 110 which plotting may be effected provided with a protractor, of an indicator provided with a downwardly-extending point for indicating the center of the protractor, and supporting means for said indicator, the supporting 115 means being located at a fixed point with respect to the center of the protractor.

3. The combination, with a table provided 120 with a protractor on its upper side, of an indicator provided with a downwardly-extending point for indicating the center of the protractor, hinged to the table outside of the protractor at a fixed point relatively to the center of the protractor whereby to be capable of being swung upward away from and downward toward such protractor, substantially 125 as described.

In testimony whereof I have signed my name to this specification in the presence of two subscribing witnesses.

ANNING S. PRALL.
